UNITED STATES PATENT OFFICE.

JOSHUA NORTON, JR., OF PORTNEUF, QUEBEC, CANADA.

REFINING PULP-ENGINE.

SPECIFICATION forming part of Letters Patent No. 398,845, dated March 5, 1889.

Application filed June 25, 1888. Serial No. 278,079. (No model.) Patented in Canada April 4, 1888, No. 28,797.

To all whom it may concern:

Be it known that I, JOSHUA NORTON, Jr., a resident of Portneuf, in the Province of Quebec, Canada, have invented certain new 5 and useful Improvements in Refining Pulp-Engines; and I do hereby declare the following to be a full, clear, and exact description of the invention, such as will enable others skilled in the art to which it pertains to make 10 and use the same, it having been patented in Canada, April 4, 1888, No. 28,797.

The object of this invention is to produce a refining or finishing engine that shall operate continuously upon unfinished material 15 received from a pulp-beating engine and produce fiber of the same character as that produced by the "Hollander" operated by skilled workmen.

In general terms, the invention involves a 20 rotating roll bearing fly-bars whose edges are everywhere equally distant from the axis of rotation, a cylindrical case inclosing said roll and provided with an inlet for unfinished material and an outlet for the finished fiber, 25 a series of bed-plates or knives fixed in said case, with the edges of the individual knives oblique to the cylindrical elements, and means for the vertical adjustment of the roll.

In the drawings, Figure 1 is a side view of 30 the apparatus, a portion of the case being broken away. Fig. 2 is an end view with the end of the case and external devices removed. Fig. 3 is a plan of the bed-plates or knives. Fig. 4 is an end view of the same. Fig. 5 is 35 a partial end view showing the adjustable shaft-support and the devices by which it is adjusted. Fig. 6 shows sliding packing-box on interior of cylinder-head. Fig. 7 is a horizontal cross-section of the cylinder-head on 40 line $x-x$ of Fig. 6. Fig. 8 is a vertical cross-section of the cylinder-head on line $z-z$ of Fig. 6.

In the drawings, A is a preferably metallic cylindrical case provided with removable heads A' and carried upon suitable supports, 45 Z. The case is further provided with bed-plate recesses B upon its lower side, and in which are bed-plates F F, with the knives b b set diagonally, as shown in Fig. 3. Within the case is a roll, D, mounted upon a vertically-adjustable shaft, C, and bearing fly-bars 50 E. Material to be operated upon is admitted

to the top of the case through a pipe, I, placed at one end of the cylinder, and the finished fiber is discharged through a pipe, J, at the lower side of the opposite end. Both these 55 pipes may be provided with ordinary valves and connections.

The shaft C revolves in bearings L, which slide vertically in guides Y, mounted upon the supports Z, and is driven by the power-pulley H. The bearings L are adjusted simultaneously by means of a crank, G, fixed upon a rod, K, mounted in the guides Y. By means of bevel-gears g g' the rod K actuates longitudinally-fixed rods K', seated in the guides 60 Y and having their lower threaded ends in engagement, respectively, with the bearings L.

The cylinder-heads A' are provided with oblong slots M, which permit the vertical adjustment of shaft C. Sliding packing-boxes 70 N are attached to shaft C and move in ways O on the interior of the cylinder-heads.

The bed-plates themselves are vertically adjusted in the usual manner by set-screws h.

In operation the material is forced into the 75 case at I and carried to the bottom by the rotating fly-bars, where it is acted upon by the oblique knives, which, owing to this obliquity, have a shearing action and tend to force the material forward toward the opposite end of 80 the case. Upon leaving the bed-plate it is carried again to the top and thence again to the knives, and so on, until at the end of its spiral course it passes out through the aperture J as finished fiber. 85

It is evident that any mechanic can vary the means for adjusting the roll vertically, that one or more bed-plates may be employed, though two only have been shown, and that the principle and operation of this apparatus 90 will nevertheless remain the same.

What I claim is—

1. The combination, in a refining-engine, of a cylinder-roll, a suitably-mounted shaft, fly-bars secured to said roll, with their edges uniformly distant from the roll's axis of rotation, a cylindrical case inclosing said roll with its fly-bars, and a series of knives set in the bottom of said case obliquely to the outer edges of the fly-bars, substantially as set forth. 95 100

2. In a refining-engine, the combination of a cylinder-roll, a shaft and means for adjust-

ing the same, fly-bars secured to said roll, with their edges parallel to and uniformly distant from the roll's axis of rotation, a cylindrical case inclosing said roll with its fly-bars, and a series of knives set in the bottom of said case, substantially as described.

3. In a refining-engine, the combination of a cylinder-roll, a shaft and means for adjusting the same, fly-bars secured to said roll, with their edges parallel to and uniformly distant from the roll's axis of rotation, a cylindrical case inclosing said roll with its fly-bars, and a series of adjustable knives set in the bottom of said case, substantially as and for the purpose set forth.

4. The combination, with the fly-bar cylinder, of the shaft C, sliding bearings L, the case A, inclosing said cylinder and provided with the bed-plates F, having knives *b* oblique to the fly-bars, the guides Y, the threaded rods K', 20 engaging the bearings L, and the crank-rod K, connected by gearing to the rods K', substantially as described.

In testimony whereof I have signed this specification in the presence of two subscribing witnesses.

JOSHUA NORTON, JR.
